AIR CONDITIONER FRONT PANEL

Charles W. Sanders, Greenville, Mich.

Application January 30, 1956, Serial No. 39,969

Term of patent 3½ years

(Cl. D62—4)

Figure 1 is a top plan view of an air conditioner front panel embodying my new design; Figure 2 is a side view in elevation; Figure 3 is an end view of the front panel taken in elevation; and Figure 4 is a sectional side view taken along lines 4—4 of Figure 2.

The design for the air conditioner front panel disclosed is characterized by the grill panel on the left front, as best seen in Figure 2, having the configuration shown.

I claim:

The ornamental design for an air conditioner front panel, substantially as shown and described.
